SHEET FEEDER

Henri E. Peyrebrune, River Forest, and Bruno B. Pasquinelli, Chicago, Ill., assignors to The Miehle Printing Press and Manufacturing Company, Chicago, Ill., a corporation of Illinois

Application September 18, 1941, Serial No. 411,314

6 Claims. (Cl. 271—53)

Our invention pertains broadly to the art of feeding sheets of paper and the like to printing presses and other sheet handling machinery.

The invention more specifically relates to that class of sheet feeding mechanism by means of which the sheets are advanced to the registering means in the form of a continuous stream of lapped sheets.

The improvements which our invention provides are more particularly intended for embodiment in sheet feeders which include a rotary type of stop gripper transfer mechanism, that is to say, a mechanism in which a sheet, after having been removed from the feeder pile, is first registered, then engaged by sheet gripping members while the transfer mechanism and the sheet are both at rest, whereupon accelerating motion is imparted to said mechanism so that the sheet will be removed from its station of registration and transferred to an impression cylinder at the surface speed of the cylinder. After the sheet has been released by the transfer mechanism, the latter is decelerated and eventually brought to rest, ready to engage the next registered sheet.

A well known mechanism whereby these steps are accomplished, in single sheet feeding, is disclosed in United States Patent No. 1,991,003, issued February 12, 1935, to B. D. Stevens and assigned to the assignee of the present invention.

It is the broad principle of said mechanism and drive therefor which we propose to introduce into the embodiment of the present invention and which shall be specifically adapted for handling sheets fed in lapped sequence.

In order to take full advantage of the principles inherent in a device such as said prior patent discloses for single sheet feeding, it will be understood that numerous constructional improvements shall have to be introduced when such a device is to be embodied in a feeder where sheets are to be handled in lapped sequence and in a manner that a succeeding sheet shall have reached the front guides before the preceding sheet has passed beyond said guide, thereby gaining time for registering the successive sheets and making possible also a reduction in the width of the gap in the printing cylinders.

It has previously been suggested, in single sheet feeders, to recede the grippers of a sheet transfer mechanism from their normal plane of operation immediately after the leading edge of a sheet is transferred to the sheet receiving member, such as an impression cylinder of a printing press, and after returning to their sheet taking positions, to maintain the grippers in their receded position

until the transferred sheet is completely withdrawn from the registering table, or until the next sheet is registered.

5 A device whereby this can be accomplished, and an operating mechanism for such a device, are described in United States Patents Nos. 1,790,457, issued to J. R. Blaine, January 27, 1931, and 1,764,104, issued to A. G. Jacobson, June 17, 1930, respectively, both patents having been assigned 10 to the assignee of the present invention. It will be noted that the Blaine and the Jacobson structures are both shown as applied to sheet transfer gripper mechanisms of the oscillating type; however, it is evident that by adequate modifications 15 in the design of said structures, the broad principles disclosed in said patents are readily adaptable for embodiment in a sheet transfer mechanism of the rotary type, such as is described in said patent to Stevens.

20 Instead of receding the grippers of the sheet transfer mechanism, the necessary clearance between said grippers and a sheet that is being withdrawn from the registering table could be provided by so mounting said table that its front 25 end, together with the sheet or sheets thereon, would dip away from the transfer grippers and remain in its dipped position until the sheet to be transferred is completely withdrawn from the table.

30 Applicants have found that, when presses are run at extremely high speeds, it is of advantage not only to recede the grippers of the transfer mechanism from their normal planes of operation during the transferring of the sheet, but also to 35 dip the registering table away from the transfer mechanism.

One of the outstanding objects of our invention, therefore, is to provide a sheet feeder of the class referred to, which shall have embodied 40 therein a novel combination of broad principles such as are separately disclosed in said earlier patents, and which shall be adapted to meet the requirements called for when feeding sheets in lapped sequence at high rates of speed.

45 An additional object resides in the provision of an improved feeder whereby the productivity of a sheet handling machine shall be considerably increased.

Another object of the invention is a combination 50 of means which shall function to provide more time for accurately registering a sheet without, however, reducing the relative press speed and therewith the productivity of the press.

55 A further object is to provide improved means whereby the sheet transfer mechanism shall be

securely locked against movement during the registering period of a sheet.

A still further object to be accomplished by the invention is the provision of means whereby irregularly fed sheets shall be detected and the feeding operation consequently interrupted.

Other objects and novel features of our invention will be apparent from the following specification and appended claims read in conjunction with the accompanying drawings which represent a preferred embodiment of the invention and wherein:

Figure 1 is a diagrammatic view in side elevation of the improved feeder and of a printing press to which the sheets are to be fed;

Figure 2 is a fractional view of Figure 1, but showing certain parts in different positions;

Figure 3 is a detail view of the sheet registering table showing preferred means whereby the front end of the table can be raised and lowered with relation to the sheet transfer mechanism.

Figure 4 depicts the arrangement of the sheet grippers on the transfer mechanism and means whereby said grippers are actuated;

Figure 5 is a similar view but illustrates the grippers withdrawn from their normal plane of operation;

Figure 6 illustrates one preferred means for imparting variable motion to the sheet transfer mechanism;

Figure 7 shows, in side elevation, the front portion of the registering table and means thereon whereby the transfer mechanism is locked in a predetermined position during the registering period of a sheet;

Figure 8 illustrates means whereby misfed sheets are detected, the parts being shown in their respective positions when a sheet is properly fed; and

Figure 9 shows the position of the detector parts when a sheet has not been fed in proper timed relation.

The printing machine selected for the purpose illustrating and describing the novel features which constitute our invention is of the rotary lithographic class. It shall be understood, however, that the improved feeder will find its usefulness on other types of sheet fed printing presses and on many kinds of sheet handling machinery other than printing presses.

Referring now to the diagrammatic showing of Figure 1, the arrangement includes a feeder pile board 10 onto which the sheets to be fed are stacked, forwarding tapes 11, registering table 12, and a rotary sheet transfer mechanism 13.

The printing press which is to receive the sheets is of the conventional "offset" type and includes an impression cylinder 14, a blanket cylinder 15, a plate cylinder 16, dampening mechanism 17, and inking mechanism 18. The printed sheets are to be conveyed to a delivery board 19 by means of a chain gripper mechanism 20.

Preferably, the sheets are separated from the pile 21 by means of suction shoes 22 arranged along the rear edge of the pile, which shoes engage the top sheet and raise its rear edge above the pile and past one or more air blast nozzles 23, which eject a blast of air between the raised sheet and the top of the pile, as is common practice in the construction of sheet feeders. The separated sheet is then taken over by a forwarding member, preferably a rotating suction roller 24 which advances the sheet into the bite of a series of tape pulleys 25 and drop rollers 26. The sheet is then forwarded over the registering table

12 by means of the forwarding tapes 11 in order to be presented to the side guides 27 and front guides 28.

As depicted in Figure 1, the sheets are fed in lapped sequence so that sheet A is against the registering guides and ready to be transferred to the impression cylinder 14 by means of the transfer mechanism 13, sheets B, C and D are being advanced in spaced relation beneath sheet 10 A and are still in the bite of said rollers 25 and 26, with the rear edge of sheet D just about to be released by the suction roller 24.

In Figure 2, the sheet A has been advanced and transferred to the grippers of the impression cylinder 14 and the sheet B has reached the registering guides 28 while it is still in part covered by sheet A. As indicated in the preamble herein, the sheet transfer mechanism 13 is actuated so that, after having engaged a registered sheet, it will remove a sheet at an accelerating speed until it has reached cylinder speed, i. e., the surface speed of the impression cylinder 14. The sheet is then taken over by the cylinder grippers 30, conveyed between the cylinders 14 and 15 to receive an impression and thereupon taken over by the chain grippers 31 of the delivery mechanism 20 in order to be deposited onto the delivery board 19, see Figure 1.

According to the position of the parts illustrated in Figure 2, the front end of the table 12 has been lowered, that is to say, the table has been swung about its pivotal support 32, thereby moving the front end away from its normal plane of operation. Furthermore, the grippers 33 of the sheet transfer mechanism have been receded to a position located within the periphery of the sheet carrying reel of said mechanism. It will be understood that, when sheets are fed in lapped sequence and when an oscillating or a rotary sheet transfer mechanism is used, the grippers 33 will again have reached their sheet engaging position either before a sheet has been completely withdrawn from the table 12, or after the next following sheet has already reached the front guides 28. Therefore, in order to avoid injury to a sheet while still on said table, the grippers of the sheet transfer mechanism and the front end of the registering table should be receded, i. e., withdrawn from their normal planes of operation and maintained in such withdrawn position until the rear edge of a transferred sheet has passed beyond the front registering guides 28.

Preferred mechanisms for accomplishing this are illustrated in Figures 3, 4 and 5 now to be described.

As shown in Figure 3, the table 12 which is pivoted at 32 to the frame of the press has provided thereon a lug 40 to which is pivoted at 41 an eye bolt 42, the free end of which extends through a block 43. This block is carried within the ends of a bifurcated arm 44 which is integral with cam roller arms 45 and 46 and is mounted on a fixed shaft 47 to rock about its axis. From opposite sides of the block 43 extend pintles 48 which are journaled in said ends of the arm 44 in a manner that the block may turn freely therein. In order to more clearly illustrate the means whereby the eye bolt 42 is connected to the arm 44, the latter is shown in section taken along a plane which passes through the bifurcation of said arm.

The arm 44 is rocked up and down by means of two cam discs 49 and 50, the former, through the intermediary of cam roller 51 carried by the arm 45, urging the arm 44 upwardly thereby to

raise the table 12. The cam roller 52, which is carried by the arm 46, rides over the cam disc 50 which transmits to the arm 44 a downward movement thereby to lower the front end of the table 12 in order to move it out of its normal plane of operation. The contour of said cam discs is such that positive movement shall be imparted to the lever arm 44 in both directions of its movement.

In the position illustrated in Figure 3, the registering table 12 is lowered so that an appreciable gap shall be provided between the top surface of said table and the reel 60 of the transfer mechanism. The leading edge of the sheet A, which is in the course of being removed from the table 12, has reached its point of transfer where the grippers 33 are about to release the sheet and the grippers 30 of the impression cylinder 14 have just engaged it. The cams 49 and 50 are so timed that the table 12 will remain in its lowered position until a sheet in the course of being transferred is completely withdrawn from the table.

The bolt 42 and the arm 44 function to provide in effect a toggle link which is broken, as illustrated in full lines in Figure 3, when the table 12 is lowered, but which is straight, as shown in broken lines, when the table is up. By means of the nuts 54 and 55, which retain the block 43 in its position on the bolt 42, the table 12 can be readily adjusted to maintain its proper position with relation to the reel 60.

In Figures 4 and 5 are illustrated partially in section those parts which constitute a preferred means whereby the grippers 33 are receded from and returned to their normal plane of operation.

In the position of the parts depicted in Figure 4, the transfer grippers 33 are closed and have a registered sheet A in their bite ready to be transferred to the impression cylinder of the press, whereas in Figure 5 the grippers 33 are open and withdrawn within the periphery of the reel 60, whereas their cooperating pads remain in their original position.

The arrangement of the cooperating parts, whereby the grippers 33 are actuated to assume these positions, is as follows:

At each end of the transfer gripper shaft 61 is provided a bracket 62, which are secured are secured thereto preferably by means of flanges 63 and 64 which embrace said shaft and which are clamped onto it by any suitable means, such as bolts 65.

While for the sake of simplicity we have chosen to illustrate only one of said brackets and associated parts, it will be readily understood as the description proceeds that the mechanism illustrated in Figures 4 and 5 is duplicated at the opposite end of the shaft 61.

Journaled in said brackets is a rotary gripper rock shaft 66 to which is secured a gripper holder or bracket 67. The latter is constituted of a member 68 and of a holder cap 69, which latter serves to clamp the member 68 onto the shaft 66, preferably by means of bolts 70. Set screws 71 are provided in said cap 69, by means of which screws the holder 67 and the parts carried thereby are securely locked in their required positions.

Preferably the grippers 33 are of the "radial" type, that is to say, they are arranged to move into and out of their operative position radially of the transfer reel 60 rather than to swing about their axis from their sheet engaging position into their inoperative position by such means of tumbler mechanism, or the like.

Each gripper is constituted of a gripper head and of an inwardly extending body portion 72, the inner end of which is preferably reduced to provide a stem 73 which passes through a block 5 74 pivotally carried by the arm 75 which extends from the bracket member 68 of the holder 67. The free end of the stem 73 is embraced by an expansion coil spring 76 which bears against the upper face of the block 74 and against a tension adjusting nut 77 which is threaded to the free end of the stem 73. The purpose of the spring 76 and nut 77 is to provide for adjustment of the tension which the transfer grippers 33 are to exert against the gripper pad blocks 78, one of which is associated with each gripper 33 for the purpose of grasping the leading edge of a sheet to be transferred from the registering table to the impression cylinder of the press.

Each pad block 78 is mounted on a stationary 20 pad support 79 and all of these supports are removably secured to a bar 80 by means of bolts 81, and which bar preferably is integral with the bracket 62.

To the outer end of shaft 66 is secured a roller 25 arm 85, which at its free end is provided with a stud 86 on which rotates a cam 88 mounted on the side frame of the transfer gripper mechanism and which cam is rotated preferably continually and 30 in proper timed relation during the operation of the mechanism. In the arrangement illustrated, the cam 88 is rotated in opposite direction to that of the stop gripper mechanism. This cam is shown in broken lines, and it will 35 be understood that two of these cams and associated arms 85 and rollers 87 may be provided, one on each side of the mechanism. As indicated, the roller 87 may be urged against its companion cam 88 by means of a tension spring 89. One 40 end of said spring is attached to a suitably located eye provided preferably on the bracket 62, whereas the other end of the spring is attached to the arm 85.

The brackets 62 also have pivotally mounted 45 therein a rock shaft 90, which may be actuated to rock about its axis by any conventional cam means, or the like mechanism, preferably by means of a cam which rotates in the same direction as cam 88, namely in opposite direction to the stop gripper mechanism.

The rock shaft 90 has secured thereto a gripper releasing blade 91 whereby the grippers are 50 displaced from their position depicted in Figure 4 and swung away from the gripper pad blocks 78 so that the grippers may be withdrawn within the periphery of the reel 60, into the position shown in Figure 5.

The function of the parts featured in Figures 4 and 5 is as follows:

First, in order to recede the grippers 33 from their normal operative path the rock shaft 90 is actuated so that the blade 91 engages the stem 72 of the grippers and displaces it to the right, as viewed in Figure 5, and to an extent that the tips of the grippers become located beyond the edge of the pad blocks 78. By that time the high portion 92 of the cam 88 will have reached the roller 87 in order to displace the arm 85 in the clockwise direction and consequently rock the gripper holder 67 about the axis of the shaft 66 so that the grippers 33 assume the position illustrated in Figure 5.

When the roller 87 reaches the low portion of the cam 88, a position shown in Figure 4, then due to the rocking of shaft 66 in the coun-

terclockwise direction the grippers 33 are again moved outwardly sufficiently far to permit the grippers to return into their cooperative relation with the pad blocks 78 upon rocking of the shaft 90 in the clockwise direction in order to release the blade 91 from engagement with the stem 12. The grippers 33 are urged into their sheet gripping position by means of tension springs 94.

It will be understood that the contour of cam 88 has a recessed portion located immediately adjacent the cusp of the high portion 92 and which is such that the grippers 33 are moved out radially somewhat beyond their sheet engaging position depicted in Figure 4 before they are swung away to be receded, and vice versa when the grippers are being returned to their sheet holding position.

As indicated herein, the tension of the grippers against the pad blocks may be adjusted by means of the adjusting nuts 77.

We will now proceed to describe one suitable mechanism whereby the desired motion is imparted to the rotary sheet transfer mechanism 13 for the purpose of transferring registered sheets from the table 12 to the impression cylinder 14. The principle of such mechanism is more fully set forth in the U. S. Letters Patent No. 2,027,818, issued to H. E. Golber and assigned to applicant's assignees.

Referring to Fig. 6 it will be seen that on the transfer shaft 61 is mounted a composite gear preferably built up of a centrodal segment 100, a circular segment 101 and a second centrodal segment 102. The remainder of the composite gear may comprise a segment 103 which is circular, and a segment 104. Also secured to the driven shaft 61 is a bracket 105 which carries a roller 106, the bracket being adjustable with respect to the composite gear by means of the adjusting device 107. A roller 108, similar to roller 106, is rotatably mounted directly on the circular gear segment 103 so that adjustment of the bracket by means of the device 107 will function to set the relationship of the rollers with each other so that there shall not be any play between said rollers and their cooperating cams during the period of dwell in the functioning of the rotary transfer gripper mechanism.

The driving shaft 109 has keyed thereto a composite driving gear 110 having a plurality of gear segments including a centrodal segment 111, a circular segment 112, a second centrodal segment 113 and a circular segment 114, comprising the greater portion of the gear. To complete the driving mechanism a gear segment 115 is provided to mesh with the segment 104 of the companion composite gear.

The hub 116 which is preferably bolted to the gear 110 has formed integrally therewith the cam 118, while similarly secured to said gear is a second cam 119. Both cams are provided at one end with a portion of more determined curvature and at their other end with an extension. In order to provide for adjustment of gear segment 112 with relation to its adjacent segments an adjusting device 120 is provided, while the entire composite gear, including the circular gear segment 114, may be adjusted by a similar device 121.

With the parts in position as shown in Figure 6 it is seen that rollers 106 and 108 ride upon the cams 118 and 119 respectively so that rotation of the driving shaft 109 continues while shaft 61 remains momentarily at rest. Initial movement in a counter-clockwise direction is im-

parted to shaft 61 when the extension formed on cam 119 engages and moves the roller 108 upwardly which permits meshing of segments 100 and 111 without any impact. The meshing of these segments, it will be understood, causes accelerating motion to be imparted to shaft 61, thereupon the circular segments 101 and 112 begin to mesh when a predetermined speed of shaft 61 has been reached. During that period when the circular segments are in mesh, the delivery of the sheet from the transfer mechanism to the rotating impression cylinder grippers takes place. In the present arrangement the meshing of the segments 102 and 113 causes gradual decelerating motion of shaft 61 subsequent to which the circular segments 103 and 114 engage and the shaft 61 is rotated at uniform speed. For the slow-down motion of the transfer mechanism the gear segments 104 and 115 are provided, the meshing of which takes place immediately prior to the engagement of the rollers 106 and 108 with their respective cams whereby said shaft will be held against rotation.

It will be understood that instead of making up said composite gears by series of segments, each gear could be cut as one continuous gear.

The mechanism illustrated in Figure 7, whereby the rotary sheet transfer device 13 and the registering table 12 are maintained in their interlocked position during the period of dwell of said device, includes a registering tooth 130 which may be bolted or otherwise secured to one end of the transfer mechanism by means of locking bolts 131, or the like. A cooperating feed table registering tooth 132 is arranged with a recess 133 formed in the table 12. This tooth is mounted in a manner that it can be adjusted to a limited degree within said recess. The means for mounting the tooth may include a pair of locking bolts 134 and washers 135, whereby the tooth 132 is rigidly locked against displacement from its adjusted position. At one end of said tooth is formed a bore 136 which accommodates a compression spring 137, which latter, for convenience of adjustment, and after the bolts 134 have been released, urges the register tooth toward the adjusting bolt 138. The adjustment of the tooth is accomplished by suitably turning said bolt which is threaded into the other end of the tooth 132 and the head of which bolt bears against a shoulder 139 formed in the table 12. The spring 137, on the other hand, bears against a shoulder 140, also provided in said table.

As depicted in Figure 7, the cooperating parts are in their positions when the transfer mechanism 13 and the table 12 are held interlocked, in which position the locking faces 141 of the tooth 130, and 142 of the tooth 132 bear against each other.

As explained herein, the table 12 is mounted to pivot, i. e., recede from its uppermost position, see Figure 3, into a lowermost position for the purpose of providing adequate clearance for a sheet which is in the course of being withdrawn from said table.

It will be understood that at the moment when the table is being receded from the position shown in Figure 7, the transfer mechanism 13 has begun its rotation for the purpose of withdrawing a registered sheet from the table 12, and that the faces 141 and 142 of the registering, i. e., locking teeth 130 and 132 shall again assume their locking relation when at the end of the revolu-

tion of the transfer mechanism 13 the table 12 is returned to its position depicted in Figure 7.

The means whereby the registering table 12 is moved about its pivot 32, is described herein with reference to Figure 3.

In Figures 8 and 9 we have illustrated one preferred form of mechanism whereby misfed sheets are detected and consequently the operation of the feeder or of the press itself is interrupted. This mechanism includes in general a bracket 150 which is mounted on tie shafts 151 and 152, both of which are secured to the side frame of the feeder, and the bracket 150 is rigidly held on said tie shafts preferably by means of set screws 153 and 154 respectively.

The bracket 150 also carries a tripping shaft 155 which is mounted within a bearing provided in said bracket and is rocked to and fro continually during the operation of the press in timed sequence with the feeder by any conventional tripping mechanism such as are well known in the art of sheet fed printing presses and therefore not described or illustrated herein. A sheet detector hook lever 156 is held in locked position on said shaft by means of a set screw 157 and preferably keyed thereto by means of a taper pin 158, or the like.

Said bracket furthermore supports a sheet detector holder arm 160 which is pivoted at 161 to said bracket in a manner to permit a limited pivotal movement for the purpose of making possible a slight adjustment of the arm 160, as will be explained later. The arm 160 is securely locked to the bracket 150 by means of bolts 162 and 163 respectively, and upon loosening of said bolts the arm may be rocked about the pivot 161 by means of the adjusting screws 164 and 165, the heads of which are arranged to bear against abutments such as dowel pins 166 and 167 respectively.

To the arm 156 is pivoted at 170 a sheet detector hook 171 which extends upwardly, and near its free end is pivoted at 172 to a link 173 which, in turn, has a pivotal connection at 174 with the arm 160. At its extreme end the hook 171 is formed with a notch 175 which accommodates a pendulum 176 pivoted to swing freely about a stud 177 carried by the upper, free end of the arm 160.

The pendulum 176 is normally urged against the hook 171 by means of a light tension spring 178 for the purpose of retaining the pendulum within said notch 175. The tension of the spring 178 may be readily adjusted by means of a detector spring rod 179 threaded into a bracket 180, where it is secured in its adjusted position by means of a set screw 181. The spring 178 may be attached to the pendulum 176 and to the screw 179 respectively by such means as eye members 182.

The manner of operation of the detector mechanism just described is as follows: As indicated herein, the rock shaft 155 is continually rocked to and fro during the operation of the press by means actuated through the tripping mechanism, so that the hook 171 is moved up and down in proper timed relation to the feeder to thereby release the pendulum 176 from the notch 175 just prior to the leading edge of a sheet reaching the upwardly extending arm 183 of said pendulum and which arm, as will be seen from the position illustrated in Figure 9, normally projects into the path of sheets to be registered.

As soon as the sheet contacts with the pendulum

portion 183, the latter having by that time been released by the hook 171 so that the pendulum can be swung about its pivot 177 and against the very light tension of the spring 178, the pendulum will be moved in a clockwise direction and held by the sheet in the position depicted in Figure 8, so that the hook 171 during its next upward stroke shall not be restrained from its upward movement and consequently no tripping will take place.

In the interest of simplicity the front guides 23, see Figure 1, are not illustrated in Figures 8 and 9, but it shall be understood that when the leading edge of a sheet has reached the position shown in Figure 8, it abuts against said guides as depicted in Figure 1, and the guides remain up until the sheet is to be withdrawn.

However, should a sheet fail to present itself in proper timed relation to the upwardly extending arm 183 of the pendulum, then the latter remains in the position illustrated in Figure 9 and consequently, during the subsequent upward stroke of the hook 171, the latter will be restrained from moving upward and the means for tripping the feeder, or the press, will be set up and rendered operative, thereby preventing misfed sheets from going through the press.

Preferably the arrangement and operation of the coacting parts is such that in the event of a sheet being misfed, the grippers 38 remain in their receded position, so that such sheet shall not be engaged by the grippers, and the front guides 23 remain up in order to prevent a sheet from sliding down beyond the front end of the registering table 12.

Should it become desirable at any time to adjust the arm 183 of the pendulum in the direction of travel of the sheets to be registered, then the bolts 162 and 163 are loosened and the adjusting screws 164 and 165 are turned in a manner that the arm 160 is rocked about its pivot 161 to thereby position the pendulum as required.

While we have described and illustrated herein preferred embodiments of mechanism whereby the objects of our invention may be attained, it shall be understood that it is our intention to cover any such modifications in the design and in the manner of operation of the various mechanisms that will come within the terms of the appended claims.

We claim:

1. In a sheet feeder for printing presses and the like, the combination of a feeder pile support, sheet forwardly means, a sheet supporting table, sheet registering means, a sheet transfer member, a train of composite gears for imparting to said member a variable motion, a sheet receiving member, mechanism for separating sheets from the feeder pile and presenting separated sheets to said forwarding means in order to advance them to said registering means, sheet holding means provided on said transfer member for engaging registered sheets in succession in order to transfer them from said supporting table to said receiving member, means for receding said sheet holding means and said sheet supporting table from their normal planes of operation while a sheet is being withdrawn from said table, and means provided on said supporting table for engaging said sheet transfer member and locking it against rearward movement during the registering period of a sheet.
2. In a sheet feeder wherein sheets are fed in lapped relation, the combination of a registering table, having a normal plane of operation

75

and having a receded position with respect thereto sheet registering means associated therewith and operative to register the top sheet on the table when the table is in said normal plane of operation and to engage the leading edge of the underneath sheet when the table is receded, a rotary sheet transfer mechanism for removing registered sheets from said table, and means for receding said table from its normal plane of operation during the removal of the registered sheet from said table for the purpose of clearing the sheet with respect to the rotary transfer mechanism while it is being withdrawn from the registering table, said latter means including adjustable elements whereby the extent of such receding can be varied.

3. In a sheet feeder wherein sheets are fed in lapped relation, the combination of a registering table having a normal plane of operation and having a receded position with respect thereto, sheet registering means associated therewith and operative to register the top sheet on the table when the table is in said normal plane of operation and to engage the leading edge of the underneath sheet when the table is receded, a rotary sheet transfer mechanism for removing registered sheets from said table, a train of composite, non-circular gears for imparting a complete revolution to said transfer mechanism, sheet engaging members associated with said mechanism, means for raising and lowering said table, and means for receding said sheet engaging members from their normal plane of operation during the removal of the registered sheet from said table for the purpose set forth, the means for raising and lowering said table including adjustable elements having toggle action whereby the extent of raising and lowering of the table can be varied.

4. In a sheet feeder, the combination of means for advancing sheets in lapped sequence, a registering table having a normal plane of operation and having a receded position with respect thereto, sheet registering means associated therewith and operative to register the top sheet on the table when the table is in said normal plane of operation and to engage the leading edge of the underneath sheet when the table is receded, a rotary sheet transfer mechanism having sheet engaging members, means for imparting to said mechanism a complete revolution before the rear edge of a sheet in the course of being transferred

has passed beyond said registering means and while a succeeding, underlying sheet is approaching its registering position, and means respectively for receding said table and said members from their normal planes of operation during the removal of a sheet from said table for the purpose set forth, the means for receding the registering table including adjustable elements whereby the extent of such receding can be varied.

5. In a sheet feeder of the class adapted to advance separated sheets in lapped sequence to a sheet handling machine, the combination of a registering table, sheet registering means, a rotary sheet transfer mechanism, means for imparting to said mechanism a complete revolution before the rear edge of a sheet in the course of being transferred has passed beyond said registering means and after a succeeding, underlying sheet has reached such registering means, and locking means associated with said table and transfer mechanism and including an adjustable, yieldingly mounted member and a rigid member, arranged in a manner that upon return of said table from its receded position into its sheet registering position, said members engage and lock said sheet transfer mechanism against rearward rotation to thereby retain the sheet transfer member in register during the registering period of a sheet.
6. In a sheet feeder wherein sheets are fed in lapped relation, the combination of a registering table having a normal plane of operation and having a receded position with respect thereto, sheet registering means associated therewith and operative to register the top sheet on the table when the table is in said normal plane of operation and to engage the leading edge of the underneath sheet when the table is receded, a rotary sheet transfer mechanism for removing registered sheets from said table, a train of composite gears for imparting to said mechanism accelerating, uniform and decelerating motion, and means for receding said table from its normal plane of operation during the removal of the registered sheet from said table for the purpose of clearing the sheet with respect to the rotary transfer mechanism while it is being withdrawn from the registering table, said latter means including adjustable elements having toggle action whereby the extent of such receding can be varied.
